UNITED STATES PATENT OFFICE.

ORRIN G. FRANKS, OF WILLIAMSPORT, PENNSYLVANIA, ASSIGNOR TO W. J. ROUSE,
OF WILLIAMSPORT, PENNSYLVANIA.

FOLDING SHEET-METAL BOX.

1,113,608.

Specification of Letters Patent.

Patented Oct. 13, 1914.

Application filed September 12, 1912. Serial No. 720,026.

To all whom it may concern:

Be it known that I, ORRIN G. FRANKS, a citizen of the United States, residing at Williamsport, in the county of Lycoming and State of Pennsylvania, have invented new and useful Improvements in Folding Sheet-Metal Boxes, of which the following is a specification.

This invention relates to improvements in folding sheet metal boxes, and it proposes a box which, while capable of somewhat general application, is especially adapted as a container for crackers or cookies, or similar perishable goods, and is useful not only to preserve its contents in good condition, but to make an effective and pleasing display thereof.

The objects of the invention are to provide a folding sheet metal box which may have a relatively large capacity and on the other hand, may be folded into a relatively small compass, forming, when folded, a flat rectangular body of slight depth; to provide a box wherein the folding parts are so jointed and related that the perishable contents are efficiently protected against dust and vermin; to provide a box which may be collapsed or extended with ease and facility; which embodies parts of such construction that the movements of the folding walls to extended relation are positively arrested at the proper time; and which does not require any special fastening adjuncts to maintain the folding walls in extended relation; to provide a box which may be sterilized thoroughly and with facility and which has provision for the ready removal and replacement of any parts, such as transparent panels or name plates that might be detrimentally affected by the sterilizing operation; to provide a box having an improved front wall construction wherein the name plate and display panel are removable from the front wall and the name plate coacts with the front wall in retaining the display panel; to provide a box which shall be of neat and pleasing appearance and in which provision is made for concealing the joints between the folding walls; and to provide a box which, when folded, may nest with other folded boxes of similar construction, thereby facilitating the storage or shipping

of the boxes in quantities and with the greatest economy of space.

Other objects and advantages will appear as the description proceeds.

An embodiment of the invention is illustrated in the accompanying drawings, wherein:

Figure 1 is a perspective view of the box as set up for use; Fig. 2 is a front elevation of the box, partly broken away, to show the joint between the front wall and the bottom; Fig. 3 is a horizontal section on the line 3—3 of Fig. 2, looking in the direction of the arrow; Fig. 4 is a vertical section on the line 4—4 of Fig. 2, looking in the direction of the arrow; Fig. 5 is a horizontal section of the front portion of the box on the line 5—5 of Fig. 2, looking in the direction of the arrow; Fig. 6 is a detail elevation of the bottom of the box; Fig. 7 is a vertical fragmentary section on the line 7—7 of Fig. 3, looking in the direction of the arrow; Fig. 8 is a plan view showing the parts midway between their extended and collapsed relation; Fig. 9 is a plan view of the box as collapsed for shipping or storage; Fig. 10 is a detail sectional view showing a slight modification of the joint between the side walls and the back, and Fig. 11 is a detail sectional view showing a device to be arranged near the top of the box for positively holding the side walls in extended relation.

Similar characters of reference designate corresponding parts throughout the several views.

The box comprises side walls 1, a rear wall 2, a front wall 3, a bottom 4, and a top 5. The side walls 1 are each made in sections, of which there are two in the embodiment shown, the section 1^a being located adjacent the rear wall 2 and the section 1^b being located adjacent the front wall 3. The sections 1^a and 1^b of each side wall are hingedly connected on a vertical axis. Similar connections are provided between the sections 1^a and the rear wall and between the sections 1^b and the front wall. The bottom 4 is hinged at its front to the lower extremity of the front wall and the top 5 is hinged at its rear side to the upper extremity of the rear wall. When the box is set up for use the sections 1^a and 1^b of each side wall

occupy a common plane. When the box is collapsed the sections of each side wall are folded inwardly against one another, the bottom is folded between the sections 1^b and the front wall, the rear wall is folded against the sections 1^a, and the top is folded against the rear wall.

The hinge connection between the sections 1^a and 1^b preferably comprises a terminal bead 6 which is provided on one of the sections and a hinge pin 7 which is carried by the other section and passes through the bead. As shown, the bead 6 is provided on the section 1^a and the section 1^b is provided at its upper and lower edges with out-turned flanges 8 and 9 respectively, between which the bead 6 fits, and by which the pin 7 is confined. The pin 7 is located inwardly of the inner edge of the section 1^b and the marginal portion 10 of said section, which projects beyond the pin, lies flush against the inner side of the adjacent offset marginal portion of the section 1^a, the latter being formed with a shallow vertical shoulder 11 to provide this relation. The marginal portion 10 of the section 1^b acts as a stop to prevent the sections from being moved outwardly beyond a common plane, and, in connection with the overlying marginal portion of the section 1^b, it is effective to establish a seal at the joint of the sections against the escape of dust and moisture into the interior of the box.

The hinge connection between the sections 1^a and the rear wall 2 preferably comprises a terminal bead 12 provided on one of the walls and a hinge pin 13 which is carried by the other wall and projects through the bead. As shown, the beads 12 are provided at the side edges of the wall 2 and the sections 1^a are provided at their upper and lower edges and at adjacent their rear edges with inturned lugs 14 and flanges 33 respectively, between which the beads 12 fit and which confine the pins 13. The sections 1^a at their rear edges are provided with inturned vertical flanges 15 which conceal the beads 12 and the other elements of the hinge joint, establish a seal against the escape of dust and moisture into the interior of the box, and afford bearings for the rear wall when the box is set up for use.

Fig. 10 shows a slight modification of the hinge connection between the sections 1^a and the rear wall 2. In this case, the sections 1^a are formed with the lugs 14 and the flanges 33 and 15 as in the preceding instance, but the flanges 15 are provided at their upper and lower ends with lugs 15^a which overlie the lugs 14 and flanges 33 and the beads 12 and hinge pins 13 are not employed. Instead, the wall 2 has at its upper and lower edges flanges 16 which are connected by rivets 17 to the lugs 14 and 15^a.

65 The hinge connection between the sections

1^b and the front wall 3 is similar to the connection between the sections 1^a and the rear wall 2, and includes terminal beads 18 provided at the sides of the wall 3 and fitting between inturned lugs 19 and flanges 49 provided at the upper and lower edges of the sections 1^b and the hinge pins 20 which pass through the beads 18 and are confined by said lugs and flanges. The sections 1^b at their forward edges are formed with in-turned flanges 21 which overlie the front wall 3 and form a bearing therefor when the box is set up, their function being the same as that of the flanges 15.

In order that the box may have a neat appearance and that the effect may be given that the walls are integrally connected or are set in frame pieces, the several sections of the side walls, adjacent their outer edges, are formed with offsets 22 of the same dimensions as the flanges 15 and 21, which they adjoin, the effect on the eye being that the offsets 22 and the flanges adjacent thereto are angle pieces in which the walls are set or to which they are joined.

The hinge connection between the bottom 4 and the front wall 3 comprises interfitting beads 23 and 24 on said bottom and front wall respectively, and a hinge pin 25 which passes through the beads 23 and 24 and has its ends secured to flanges 27 at the sides of the bottom 4.

When the box is set up the bottom 4 is supported by the hinge joint described and also by an inturned flange 28 provided at the lower edge of the rear wall 2 and upon which the free edge portion of the bottom rests. The bottom 4 may have at its free edge an inturned flange 29 provided with a slot 30 in which the thumb nail may be engaged for the purpose of lifting the bottom when the box is to be collapsed or of pushing the bottom downwardly when the box is to be set up. It may be noted that the flanges 27, 28, and 29 have uniform contact with the adjacent parts, when the box is set up, and are effective to prevent dust, moisture or vermin from passing into the box through the bottom thereof. The organization is of such nature, however, that the provision of these flanges does not increase the space taken up by the box when its walls are collapsed.

In order to prevent the bottom 4 from being accidentally jarred from position 120 when the box is set up, spring tongues 31 are provided at the lower edges of the sections 1^a and slots 32 are cut at the sides of the bottom 4 through which the tongues project, the office of the tongues 31 being to engage frictionally against the flanges 27 as best shown in Fig. 7. In the embodiment shown, the sections 1^a are provided at their lower edges with the inturned flanges 33 aforesaid which, when the sections 1^a and 130

1^b are in a common plane, are in line with the inturned flanges 49 aforesaid of the sections 1^b and in connection with said flanges 49 form rests for the bottom 4 and also 5 engage the surface of the shelf or support upon which the box rests, the area of engagement being sufficient to prevent dust or vermin from passing under the box. The tongues 31 aforesaid are carried by the flanges 33 and are struck out from the sections 1^a.

The hinge connection between the top 5 and the rear wall is shown at 34 and is of ordinary character, being generally similar 15 to the connection between the bottom 4 and the front wall 3.

The top 5 is formed along its sides and front with inturned flanges 35 which are preferably beaded at their edges and which 20 not only serve to prevent the entrance of dust or vermin, but also to retain the top in its closed position and against accidental displacement, coacting in these functions with the upper edge portion of the front 25 wall of the box, with the flanges 8 at the upper edges of the sections 1^b, and with flanges 36 at the upper edges of the sections 1^a and which, in effect, form continuations of the flanges 8 when the box is set up.

The beads 24 which are provided at the lower edge of the front wall 3 and form parts of the hinge connection between said front wall and the bottom 4 are located inwardly of the plane of the front wall and 35 project from a ledge 37 which forms a support for the transparent display panel 38. The wall 3 at its lower edge is crimped, as at 39, and the ledge 37 projects from the crimp 39 which is provided to conceal the 40 hinge connection between the front wall and the bottom and also to bear upon the surface of the shelf or other support upon which the box rests and thereby prevent dust or vermin from passing under the box 45 from the front thereof.

As previously stated, the invention includes a novel front wall construction, the features of which involve the assemblage of the display panel. For the purpose of retaining the panel 38 upon the ledge 37 and in contact with the front wall, the ledge 37 is provided, between the beads 24, with upstanding spring fingers 40 which engage the lower portion of the display panel and the beads 20 are formed with inturned flanges 41 which engage over the sides of the display panel. The front wall is provided with an opening 43 over which the display panel is arranged and through 55 which the contents of the box are visible. In connection with a transparent display panel employed for the purpose stated, it is customary and desirable to indicate on the front of the box the name or designation of the goods which the box contains.

For this purpose, a name plate 44 is provided in the example disclosed, and the reading on said plate is exposed through an opening 45 formed in the front wall. The plate 44 may have at its lower end an angle 70 flange 46 which engages over the upper portion of the panel 38. The flanges 41, above referred to, serve also to confine the plate 44 and to hold the latter against the front wall. For this purpose, the plate 44 is 75 formed at its sides with overturned flanges 47 which engage under the flanges 41. The plate 44 is further held in good contact with the front wall by means of an angular flange 48 which is formed along the upper 80 edge of said plate and is fashioned to engage over the upper edge portion of said front wall. The flange 48 serves also to prevent dust from entering between the front wall and the plate and between the 85 front wall and the adjacent flange 35 of the top 5. It will be apparent from the foregoing description that the panel 38 and the plate 44 are held securely in position and in such contact with the front wall as will 90 prevent dust from entering at the edges of the openings 43 and 45. The security of the assemblage of the plate 44 and the panel 38 does not, however, interfere with the ready 95 removal of these elements whenever the occasion may demand, for instance, as when the box is to be sterilized. To collapse the box, the top is thrown back and the bottom 4 is raised to a position where it lies against the front walls 3. The side walls 1 are 100 then "broken", as indicated in Fig. 8, the sections 1^b coming adjacent the bottom 4 and the sections 1^a coming adjacent the sections 1^b and between the latter and the top 5. The parts then have the relation shown in 105 Fig. 9, from which it will be seen all of the walls are in substantially parallel relation and that the box is folded into a very small compass, forming a rectangular body of shallow depth. For example, assuming the 110 box to have a cubic foot capacity, it will in practice fold to a depth of about seven-eighths of an inch.

It will be observed that the top 5 folds outwardly and consequently its flanges 35 115 may be fitted over the front wall of a folded box adjacent thereto. In this manner it is possible, when packing the boxes for shipment or storage, to nest them and thus effect great economy of space.

To extend the box, its front and rear walls are pulled away from one another to a slight extent and the side walls are then forced outwardly, their sections ultimately coming into parallel planes at which time their further outward movement is arrested, as already explained. The bottom is then pushed downwardly until it comes to rest on the flanges 28. When the box is extended, its vertical walls are protected against any in- 125 130

ward pressure, since, as already described, the flanges 15 and 21 form bearings for the rear and front walls and the overlying portions of the sections 1^a and 1^b serve a similar function.

In some cases it may be desirable to provide means, in addition to the bottom 4, for positively holding the sections 1^a and 1^b of each side wall in extended relation. An example of such a means is shown in Figs. 1 and 11, from which it will be seen that a slide 50 is arranged on the outer side of the sections 1^a near the upper edge thereof, and carries a headed pin 51, the shank of which passes through a narrow slot 52 in the section 1^a and through a keyhole slot 53 in the underlying portion 10 of the section 1^b. When the slide is moved downward the head of the pin alines with the under portion of the slot 53 and, when the bottom has been raised, the sections 1^a and 1^b may be folded inwardly, the pin 51 in such case passing from the slot 53. On the other hand, when the sections 1^a and 1^b have been extended and the pin 51 has passed through the slot 53, the slide is raised, remaining in its raised position by the frictional contact of the parts, and the pin 51 occupies the narrow portion of the slot 53, and thus locks the sections 36 against inward displacement and prevents any inward distortion of the upper portions of the side walls.

It will be understood that no specific description herein contained is intended to put any limitation upon the scope of the appended claims which does not inhere in the language thereof.

Having fully described my invention, I claim:

1. In a folding box, side walls made in hingedly jointed front and rear sections, a front wall hingedly jointed to the front sections, and a rear wall hingedly jointed to the rear sections, the said sections having in-turned flanges at their extreme edges which are adapted when the box is set up to overlie the side marginal portions of the front and rear walls and to form bearings for said walls.
2. In a folding box, side walls made in hingedly jointed front and rear sections having in-turned lugs at their upper and lower ends and adjacent their extreme edges, and having hinge pins extending between said lugs, and front and rear walls hingedly jointed to said respective front and rear sections and having terminal beads at their side edges which fit between said lugs and through which the hinge pins pass, the said sections having in-turned flanges at their extreme edges which, when the box is set up, are adapted to overlie the side marginal portions of the front and rear walls to form bearings therefor, and to conceal the hinge

joints between said front and rear walls and 65 said side walls.

3. In a folding box, side walls made in hingedly jointed sections, front and rear walls hingedly jointed to the respective front and rear edges of said side walls, a bottom hinged to the lower edge of the front wall and having side flanges and slots adjacent thereto and spring fingers provided at the lower edges of the side walls to engage through the slots of the bottom, 75 the side walls having flanges at their lower edges which carry the fingers, the latter being struck out from the side walls.

4. In a folding box, side walls made in hingedly jointed sections and having outwarded flanges at their upper edges, front and rear walls hingedly jointed to the respective front and rear edges of said side walls, a top hingedly jointed to the upper edge of said rear wall and having flanges 80 at its sides and front to fit over said side and front walls when the box is set up, and, when the box is folded, to receive the front wall of an adjacent folded box in nested relation, and a bottom hingedly jointed to the 90 lower edge of the front wall and adapted to fold between the latter and the adjacent sections of the side walls.

5. In a folding box, hingedly jointed side and front walls, a bottom, an inset hinge 95 joint connecting the bottom and the front wall, the front wall having a crimp at its lower edge and having a ledge which projects from the crimp and to which the bottom is hinged, spring fingers struck up from the ledge, and a panel resting upon the ledge and having its lower portion engaged by said fingers, the hinge joints between the front and side walls including beads which are formed with inturned side flanges to engage over the marginal side portions of 100 said panel.

6. In a folding box, hingedly jointed side and front walls, a bottom, an inset hinge joint connecting the bottom and the front 110 wall, the front wall having a crimp at its lower edge and having a ledge which projects from the crimp and to which the bottom is hinged, spring fingers struck up from the ledge, a panel resting upon the ledge and having its lower portion engaged by 115 said fingers, the hinge joints between the front and side walls including beads which are formed with inturned side flanges to engage over the marginal side portions of 120 said panel, and a plate fitted removably under and between said flanges and having a flange at its lower edge which engages the upper portion of the panel.

7. In a folding box, hingedly jointed side 125 and front walls, a bottom, an inset hinge joint connecting the bottom and the front wall, the front wall having a crimp at its

- lower edge and having a ledge which projects from the crimp and to which the bottom is hinged, spring fingers struck up from the ledge, a panel resting upon the ledge and having its lower portion engaged by said fingers, the hinge joints between the front and side walls including beads which are formed with inturned side flanges to engage over the marginal side portions of said panel, and a removable plate having side flanges which engage under said first named flanges and having a flange at its lower edge which engages over the upper portion of the panel.
15. 8. In a folding box, hingedly jointed side and front walls, a bottom, an inset hinge joint connecting the bottom and the front wall, the front wall having a crimp at its lower edge and having a ledge which projects from the crimp and to which the bottom is hinged, spring fingers struck up from the ledge, a panel resting upon the ledge and having its lower portion engaged by said fingers, the hinge joints between the front and side walls including beads which are formed with inturned side flanges to engage over the marginal side portions of said panel, and a removable plate having side flanges which engage under said first named flanges and having a flange at its lower edge which engages over the upper portion of the panel, the upper portion of the plate being fashioned to engage over the upper edge of the front wall.
25. 9. In a folding box, hingedly jointed side and front walls, a bottom, an inset hinge joint connecting the bottom and the front wall, the front wall having a crimp at its lower edge and having a ledge which projects from the crimp and to which the bottom is hinged, spring fingers struck up from the ledge, a panel resting upon the ledge and having its lower portion engaged by said fingers, the hinge joints between the front and side walls including beads which are formed with inturned side flanges to engage over the marginal side portions of said panel, and a removable plate having side flanges which engage under said first named flanges and having a flange at its lower edge which engages over the upper portion of the panel, the upper portion of the plate being fashioned to engage over the upper edge of the front wall.
30. 10. In a folding box, hingedly jointed side and front walls, a bottom, an inset hinge joint connecting the bottom and the front wall, the front wall having a crimp at its lower edge and having a ledge which projects from the crimp and to which the bottom is hinged, spring fingers struck up from the ledge, a panel resting upon the ledge and having its lower portion engaged by said fingers, the hinge joints between the front and side walls including beads which are formed with inturned side flanges to engage over the marginal side portions of said panel, and a removable plate having side flanges which engage under said first named flanges and having a flange at its lower edge which engages over the upper portion of the panel, the upper portion of the plate being fashioned to engage over the upper edge of the front wall.
35. 11. In a folding box, side walls made in hingedly jointed front and rear sections, a front wall hingedly jointed to the front sections and a rear wall hingedly jointed to the rear sections, the hinge connections between the front and rear walls and the respective sections of the side walls including an inturned flange provided at the extreme edge of one of the hingedly connecting parts, and which is adapted, when the box is set up, to overlie the adjoining marginal portion of the companion hingedly connected part and to form a sustaining bearing for the latter.
40. 12. In testimony whereof I have hereunto set my hand in presence of two subscribing witnesses.
